[57] CLAIM

The ornamental design for a ship's funnel, as shown and described.

DESCRIPTION

FIG. 1 is a rear perspective view of a ship's funnel showing my new design;

FIG. 2 is a left side elevational view thereof, the right side elevational view being a mirror image of that shown;

FIG. 3 is a top plan view thereof;

FIG. 4 is a bottom plan view thereof;

FIG. 5 is a front elevation view thereof.

FIG. 6 is a rear elevation view thereof.

FIG. 7 is a front perspective view thereof on reduced scale, the broken lines are for illustrative purposes only and form no part of the claimed design.
